(57) **CLAIM**

The ornamental design for a dome shaped illumination device, as shown.

DESCRIPTION

FIG. 1 is a shaded perspective view with strap of the dome shaped illumination device in accordance with the present invention.

FIG. 2 is a shaded perspective view with strap of the dome shaped illumination device in accordance with the present invention.

FIG. 3 is a shaded perspective view with strap of the dome shaped illumination device in accordance with the present invention.

FIG. 4 is a shaded front view with strap of the dome shaped illumination device in accordance with the present invention.

FIG. 5 is shaded side view with strap of the dome shaped illumination device in accordance with the present invention.

FIG. 6 is a shaded top view with strap of the dome shaped illumination device in accordance with the present invention.

FIG. 7 is a shaded bottom view with strap of the dome shaped illumination device in accordance with the present invention.

FIG. 8 is a shaded front view without strap of the dome shaped illumination device in accordance with the present invention.

FIG. 9 is a shaded back view without strap of the dome shaped illumination device in accordance with the present invention.

FIG. 10 is a shaded top view without strap of the dome shaped illumination device in accordance with the present invention; and,

FIG. 11 is a shaded side view without strap of the dome shaped illumination device in accordance with the present invention.
